UNITED STATES PATENT OFFICE

2,340,409

CHAIN HOIST

George W. Benjamin, Birmingham, Ala., assignor to Continental Gin Company, a corporation of Delaware

Application August 8, 1941, Serial No. 406,036

4 Claims. (Cl. 254—74)

My invention relates to a chain hoist of the type embodying a ratchet and lever mechanism for advancing or retracting a chain, one link at a time, in a suitable guideway, and in particular is an improvement on the hoist described and claimed in my prior Patent No. 2,227,893, issued January 7, 1941.

The principal object of my invention is to provide a simple, sturdy hoist of the character described which shall have improved operating characteristics over that of my prior patent.

In my prior patent aforesaid, I employ an operating lever pivoted on the body of the hoist and I pivotally mount a pawl on each side of the pivot point of the lever, the pawls being adapted to engage the links of a chain alternately to advance or retract it with respect to the body of the hoist. The pawls are biased toward the chain when lifting and are so shaped that when one pawl engages a link to advance it, the other pawl is caused to disengage its associated link and permit the chain to advance. While the apparatus of my said patent is entirely successful in operation, it has the disadvantage that it is double acting and the operator must change his stance for each change of direction of movement of the lever. That is, in lifting a load the operator must raise the operating lever on one stroke and pull it downwards on the next stroke, with an equal load in each direction, which operation is awkward and difficult, particularly in handling heavy loads.

In accordance with my present invention, I employ a hoist body similar to that of my prior patent with an oscillating lever pivotally mounted thereon. Instead of mounting both pawls on the operating lever, I mount one on the lever and one on the body of the hoist. The pawls are resiliently connected to bias them towards the hoist chain. With only one pawl movable with respect to the body of the hoist, the chain is advanced only upon movement of the lever in one direction. When the lever is moved in the opposite direction, the pawl mounted on the body of the hoist holds the chain while the movable pawl engages another link of the chain. The apparatus may thus be operated by exerting force in one direction only on the operating lever. With a vertical lift, the work stroke is made downwards, and it will at once be apparent that this is a distinct advantage in handling heavy loads.

Apparatus embodying features of my invention is illustrated in the accompanying drawings forming a part of this application, in which

Fig. 1 is a view partly in section and partly in elevation showing my improved hoist;

Fig. 2 is a sectional view taken along the line II—II of Fig. 1;

Fig. 3 is a sectional elevation taken at right angles to Fig. 1;

Fig. 4 is a fragmentary elevation of the hoist showing it arranged for retracting the chain;

Fig. 5 is a sectional view drawn to a larger scale showing the action of the hoist in retracting the chain at the moment before load is transferred from the holding pawl to the lifting pawl;

Fig. 6 is an elevational view of the holding pawl;

Fig. 7 is an elevational view showing the action of the hoist in lowering the chain at the moment before load is transferred from the lifting pawl to the holding pawl and showing the lifting pawl in dotted position after the load is transferred;

Fig. 8 is a view showing the positions of the pawls when lowering the chain and when the operating lever is in horizontal position.

Referring to the drawings for a better understanding of my invention, my improved hoist comprises a body 10 provided with a sustaining hook 11. Formed in the body 10 is a guideway 12 for a chain 13. The chain 13 may be of the flat, or ladder type as shown, with cross pins 14 connecting the separate links, or it may be of any suitable type which may be engaged by a pawl and advanced in the manner hereinafter described. The lower end of the chain 13 is adapted to be attached to the work as by a hook 16, partially shown in Fig. 1.

Pivoted on the body 10 is an operating lever 17 having arms 18 and 19 straddling the body 10 and pivoted on pins 21 and 22 which may be bosses formed on the sides of the body. A lifting pawl 23 is pivoted at one end 24 to the arms 18 and 19 of the operating lever 17, and extends upwardly, as viewed in the drawings, alongside the body 10. A finger 26 formed on the pawl 23 extends through an opening 27 in the body to engage a cross pin 14 of the chain 13 and move the chain within the body responsive to downward movement of the lever 17. The under side of the finger 26 is inclined at 28 to cause it to engage the next lower cross pin 14 and be moved out of the body 10, upon movement of the lever 17 in the opposite direction.

Formed on the body 10 on the side opposite the pawl 23 are a pair of lugs 29 between which is pivoted a second or locking pawl 31 which is

similar in configuration to the pawl 23 and which is provided with a finger 32 adapted to enter the body 10 through a suitable opening at 33 and engage a cross pin 14 of the chain 13 to hold the chain in any set position. The pawl 31 is also provided with an inclined face 35 which, upon upward movement of the chain 13, as viewed in Fig. 1, causes the pawl 31 to be moved outwardly of the body 10 and assume a position to engage the next cross pin when it comes into position just above the finger 32.

Carried by the pawl 23 is a pin 34 and carried by the pawl 31 is a pin 36, which pins are connected by a spring 37 which normally biases the pawls 23 and 31 inwardly of the body of the hoist to engage the cross pins 14. As so far described, when the operating lever 17 is raised from the position shown in Fig. 1 of the drawings, the pawl 23 moves downwards while the finger 32 of the pawl 31 engages a cross pin 14 of the chain 13 to hold it in position in the body 10. The finger of the pawl 32 engaging the next lower pin 14 causes pawl 31 to ride over that pin and when it has passed the pin it is pulled into position beneath the pin by the spring 37. If the operating lever be now pulled downwards, the finger 26 engages the last mentioned pin 14 and moves it upwards, while the pawl 31 pivoted to the side of the body 10 of the hoist is disengaged from the next lower pin 14 and is caused to move outwardly of the body 10 by the approaching pin 14, to engage it as soon as it passes above the finger 32. The chain and its load is thus raised a link at a time by oscillation of the operating lever 17 and the pawl 31 acts to hold the chain in its raised position while the operating lever 17 is being moved upwards to engage another link. Fingers 38 and 39 on the opposite ends of the pawls 23 and 31 respectively serve as a means to disengage both pawls from the chain 13 when getting ready to operate and it is desired to move the chain through the body a considerable distance without oscillating the lever 17.

Mounted on one side of the lever 17 and secured thereto preferably by welding is a plate 41 having an oblong opening 42 therein with a notch 43 in the plate giving access to the opening. Disposed midway of the ends of the spring 37 is a T-shaped member 44 with the head of the T within the coils of the spring 37 and the shank 46 extending outwardly through the coils. When raising a load with the hoist, as just described, the shank 46 of the T is turned to the position shown in Figs. 1 and 3, that is, out of engagement with the sides of the opening 42 in the plate 41. When it is desired to lower a load gradually, the pin 46 is turned to the position shown in Figs. 4 and 5 of the drawings, with the shank 46 passed through the notch 43 into the opening 42. The shank 46 can be thus entered when the lever 17 is moved to mid position and will be engaged by the end of the opening 42 to compress one end of the spring 37 when the lever 17 is in its lower position. With the shank 46 of the T-member 44 in the opening 42, and with the operating lever 17 in the position shown in Fig. 5, it will be seen that the end of the spring 37 attached to the pawl 23 is in tension while the other end attached to the pawl 31, is in compression, tending to push the finger 32 of the pawl 31 out of engagement with the cross pin 14. At this moment in the cycle of operation, the finger 32 is held in engagement with cross pin 14 by the weight of the load on said cross pin.

If the lever 17 be now moved downward slight-

ly from the position shown, the pawl 23 will raise the chain enough to release the engagement of the finger 32 of holding pawl 31 with its associated pin 14 and the pawl will be moved out of engagement with the chain by the spring 37, permitting the chain to be lowered by gravity as the operating lever 17 is raised. See Fig. 8. As the lever 17 is being raised, the engagement of the left end of the opening 42 with the shank 46 is relieved. See Fig. 5. The end of the spring 37 attached to the pawl 31 is again put in tension and pulls the pawl inwardly of the housing 10 to engage with the next higher cross pin 14, thus lowering the chain 13 one link.

At the same time, as the lever 17 approaches its highest position, the right hand end of slot 42, as viewed in Fig. 7, engages the shank 46 and places the left end of spring 37 in compression. As soon as the lever has been raised sufficiently for the holding pawl 31 to engage the adjacent descending pin 14 and take over the load, the part of spring 37 in compression acts on lifting pawl 23 to move it outwardly of housing 10 and out of engagement with the chain, as shown in dotted position, Fig. 7. The lever 17 may now be lowered and spring 37 will hold lifting pawl 23 out of engagement with the chain until it has passed the pin 14 with which it has been engaged, at which time the slot 42 will have moved out of engagement with shank 46 permitting spring 37 to pull pawl 23 back into the housing to engage with the next higher pin 14, as shown in Fig. 8.

While in the description herein the action of the hoist has been described as when raising or lowering a load, it will be obvious that the action is the same when acting on a horizontal pull as when stretching or loosening a wire or cable.

From the foregoing it will be apparent that I have devised an improved chain hoist which is simple and sturdy of design and which is easily operated without the operator being obliged to change his position during the operation.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. A chain hoist comprising a housing, a chain movably mounted in the housing and adapted for attachment at one end to a load, a locking pawl pivotally mounted on the housing and adapted to engage the chain and prevent retraction thereof, a lever pivoted to the housing, a pawl pivoted to the lever and adapted to push the chain through the housing when the lever is oscillated, and a spring for biasing the pawls toward engagement with the chain, and means adapted to coact with the spring and the lever alternately to effect disengagement of said pawls when retracting the chain.

2. A chain hoist comprising a housing having a longitudinally extending guideway, a chain movable through the guideway and adapted for attachment at one end to a load, a locking element pivoted to the housing and having a portion adapted to engage the chain and prevent rearward retraction thereof, an operating lever, pivoted to the housing, a pawl pivoted to the lever and adapted to feed the chain through the guideway upon oscillation of the lever, a spring con-

nected to the locking element and the pawl and biasing them toward engagement with the chain, and means associated with the spring and the lever for exerting force alternately on the locking element and the pawl to disengage them alternately from the chain during lowering operation.

3. A chain hoist comprising a housing having formed therein a longitudinally extending guideway, a chain slideable in the guideway, a pawl pivotally mounted on a side of the housing and adapted normally to lock the chain against rearward retraction during operating, a lever pivoted to the housing, a second pawl pivoted to the lever and engaging the chain on the side thereof opposite to the first mentioned pawl, said second pawl being adapted to push the chain through the housing upon movement of the lever about its pivot, a spring to bias the pawls into chain engaging position, a member carried by the spring and engaging the coils intermediate the ends, said member being movable into the path of the lever, and means on the lever adapted

to coact with the said member to exert a force alternately on the locking pawl and said second pawl to disengage them from the chain during lowering operation.

5. A device of the character described comprising a housing having formed therein a longitudinally extending guideway, a chain movable in the guideway and adapted for connection at one end to a load, a pair of pawls entering between the links of the chain on opposite sides thereof, means to pivotally mount one of the pawls on the housing, an operating lever pivoted adjacent one end to the housing and having a handle portion and an extension portion, means to pivotally mount the other of said pawls on the extension portion of the lever, means for biasing said pawls into chain engaging position, and means responsive to operation of the lever during lowering operation to engage the biasing means and effect alternate disengagements of the pawls therefrom.

GEORGE W. BENJAMIN.
